(57) **CLAIM**

The ornamental design for a connector device for a programmable logic controller, as shown and described.

DESCRIPTION

FIG. 1 is a front elevational view of a connector device for a programmable logic controller showing my new design;
FIG. 2 is a rear elevational view of the connector device for a programmable logic controller;

FIG. 3 is a top plan view of the connector device for a programmable logic controller;

FIG. 4 is a bottom plan view of the connector device for a programmable logic controller;

FIG. 5 is a right-side elevation view of the connector device for a programmable logic controller;

FIG. 6 is left-side elevation view of the connector device for a programmable logic controller; and,

FIG. 7 is a perspective view of the connector device for a programmable logic controller.
